[57] CLAIM

The ornamental design for a water ejecting gun or similar article, as shown and described.

DESCRIPTION

FIG. 1 is a right side elevational view of a water ejecting gun or similar article showing my new design;

FIG. 2 is a left side elevational view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view thereof;

FIG. 8 is a perspective view of a water ejecting gun or similar article showing a second embodiment of my new design, the sole difference being that the nozzle is formed of two sections; and

FIG. 9 is a perspective view of a water ejecting gun or similar article, showing a third embodiment of my new design, the sole difference being that the nozzle is formed of three sections.
